UNITED STATES PATENT OFFICE

2,598,918

AUTOMATIC WASHING MACHINE

Clare S. Jacobs and Merton F. Wilcox, Detroit,
Mich., assignors, by mesne assignments, to
Horton Manufacturing Company, Fort Wayne,
Ind., a corporation of Indiana

Original application June 27, 1946, Serial No.
679,698. Divided and this application July 24,
1948, Serial No. 44,764

5 Claims. (Cl. 74—337.5)

1

The invention relates to washing machines and it has particular relation to a clothes washing machine which operates automatically through a given cycle of operations. In certain respects the invention is related to those embodied in the copending applications for patent filed in the names of Hyman D. Brotman, Serial Nos. 573,362, filed January 18, 1945, now abandoned, and 639,065, filed January 4, 1946, now Patent No. 2,468,919, and the copending application of Merton F. Wilcox, No. 606,525, filed July 23, 1945, now Patent No. 2,582,810. This application is a division of the copending application of Clare S. Jacobs and Merton F. Wilcox, Serial No. 679,698, filed June 27, 1946.

In the washing machines embodied in the copending applications for patent, a perforated cylinder is provided for containing the clothes to be washed and during the washing and rinsing operations, the cylinder automatically is rotated first in one direction through a plurality of revolutions and then in the other direction through a plurality of revolutions. After the final rinse, the cylinder is automatically rotated in one direction at high speed for the purpose of extracting moisture from the clothes so as to leave them in a semi-dry condition. The cycle of operations may be altered as may be evident, and, for example, one or more short extracting stages may be introduced, such as a short extracting stage immediately following the washing stage and a short extracting stage immediately following the first rinsing stage. The present invention involves improvements in the construction of the frame and the cabinet of the machine, improvements in the operating mechanism and improvements in the manner in which the parts are arranged and assembled.

Another object of the invention is to provide an improved type of automatically operated mechanism for governing movement of the cylinder wherein the reverse and high speed operations may be performed efficiently and without undesirable strain on the operating parts.

Another object of the invention is to provide an improved type of operating mechanism which is mounted on the framework of the machine in a simple manner so as to promote smoothness of operation and at the same time minimize shocks in the mechanism when changing from one stage of operation to another.

Another object of the invention is to provide an improved operating mechanism wherein the changes from one direction to another and the change from slow speed rotation to high speed

55

extracting rotation is effected in a simple manner while still insuring positiveness and durability in the operation of the machine.

Another object of the invention is to provide an improved washing machine wherein the operating parts are readily accessible for repair or replacement or for any other attention that might be necessary.

Other objects of the invention will become apparent from the following specification, from the drawings relating thereto, and from the claims hereinafter set forth.

For a better understanding of the invention, reference may be had to the drawings wherein:

15 Figure 1 is a front elevational view with certain parts broken away and other parts shown in cross-section, illustrating a washing machine constructed according to one form of the invention;

20 Figure 2 is a cross-sectional view taken substantially along the line 2—2 of Figure 1, with some parts broken away;

Figure 3 is a top or plan view of the machine shown by Figure 1;

Figure 14 is a detail view in section showing the means for shifting the reversing clutches;

Figure 15 is an end view of the cam for controlling the temperature of the inlet water;

Figure 16 is a developed plan view of the cam shown by Figure 15; and

Figure 17 is a diagrammatic view illustrating the arrangement of cams, valves, and electric circuit.

Referring to Figures 1 and 2, it may be stated

initially in general terms that the machine comprises an inner framework 10, a tub 11, a rotary cylinder 12, automatically operating mechanism 14 for governing movement of the cylinder, and an outer casing 13. These generally indicated parts of the machine will be considered in order.

The inner framework comprises two end frames 18 and 19 and these frames are substantially identical. Each frame is substantially rectangular in cross-section and along its vertical side edges it has flanges 20 and 21 which are directed towards the same side of the frame. The bottom portions of the frames are connected by reinforcing channel elements 22 and 23. Each of the frames 18 and 19 at each lower corner is provided with a foot 30 adapted to rest on the floor so as to hold the machine solidly in position.

The tub 11 comprises a generally cylindrical band 32 having at each end circumferentially spaced angle brackets which are secured to the two frames by rivets. The circular ends of the band project into annular beads respectively formed on the frames 18 and 19 and in order to seal each end of the band against its frame, an annular rubber sealing ring is provided in each of the beads and this sealing ring receives the adjacent end of the band.

The cylinder 12, as best shown by Figures 1 and 2, comprises generally dish shaped end walls 50, each of which is provided with a peripheral flange 51, and such end walls fit within and are secured to a perforated cylindrical wall 52. Such cylindrical wall 52, at circumferentially spaced points, has inwardly directed, perforated baffles 54 which are useful in lifting the clothes during rotation of the cylinder, as will be readily understood. Each of the end walls 50 carries a spider 55 which is riveted to the outer marginal portion of the end wall as indicated at 56 and such spiders have hub portions 57 located in axial alignment with the axis of the cylinder.

As best shown by Figure 1, the right end wall of the cylinder has a trunnion 58 which projects through the hub 57 and through a central opening in the end frame 19 and such trunnion is welded or otherwise drivingly connected to the hub. Within the opening in the end frame, the trunnion is supported in a bearing sleeve 60 and this bearing sleeve is in turn supported by a rubber sleeve 61. In turn, the rubber sleeve is mounted in an axially directed hub 62 having a radially directed flange 64 secured to the end plate by circumferentially spaced bolts 65. This arrangement provides a resilient mounting for the trunnion 58 so that during rotation of the cylinder, the rubber acts as a cushioning element.

The trunnion for the opposite end of the cylinder is indicated at 66 and corresponds substantially to the trunnion 58 and is similarly mounted in the hub of the spider at such end of the cylinder. However, the trunnion 66 is employed to drive the cylinder and for this purpose it projects beyond the outer side of the frame 18 and has a large pulley 70 keyed thereto. Consequently, when the pulley is driven the cylinder is rotated.

The cylinder has an opening for inserting and removing the clothes and this opening is adapted to be closed by a door.

The foregoing description generally indicates the character of the frame and tub, and the rotary cylinder mounted therein. Further reference will be had to certain details relating to the tub and frame in conjunction with other

parts of the machine when such other parts of the machine are described hereinafter.

As shown by Figures 1 and 2, the construction so far described is enclosed by the casing 13. The casing comprises a front panel 103, a side panel 104, a side panel 105, back panel 106 and a top or cover 107.

The front panel 103, as best shown by Figure 2, at its lower end has a foot receiving cavity 115 which has its inwardly disposed wall secured to the channel 23 by screws 116. This anchors the lower end of the front panel in position. Upwardly from the cavity 115, the front panel has a door recess 118 which normally is closed by a door 119 and this door carries hinge elements 120 which are hinged by means of a pin 121 to hinge bracket 122 carried by the panel. A spring 123 connected to the hinge brackets at one end and connected at its other end to brackets 124 on the panel normally holds the door closed. At one point the door has a louver opening 125 to enable gripping the door and opening it manually. This door is provided for obtaining access to a drain chamber which will be mentioned later.

At the upper edge of the opening 118, the front panel has an inwardly directed flange 127 which is secured to a tie band or cross bar 128 which extends between the front flanges 20 and 21 of the two frames 18 and 19 and is secured to such flanges and from this it follows that the panel is thus firmly connected to the frames. Towards the top of the front panel it is provided with an opening 130 which accommodates a control panel 131 although this control panel is not secured to the front panel.

The central region of the top 107, as seen in Figure 2, has an opening 145 which is normally closed by a door 150 which is hinged to the top by hinge elements 151 carried by a hinge pin 152 engaging a hinge plate or strip 153. As best shown by Figure 1, the top 150 seals against the sealing ring 45 and at its center it has a depending annular flange 157 which receives a glass 158. This glass is held in place by a retaining ring 159.

The door 150 is adapted to be held in closed position by a latching mechanism 161 operated by a handle 190 cooperating with a keeper 162 depending from the door.

As shown by Figure 2, the operating mechanism is mounted in the cabinet below the tub 11 and such mechanism includes generally a motor 200 and a power transmission 201. The motor is mounted by means of a U-shaped bracket 202 which is carried by a frame structure 203 rigidly secured to a bar or pivot 204 journaled in the two frames 18 and 19. The transmission includes a casing 207 which is hinged at its lower end, as indicated at 208, on the frame 203 and the upper end of the casing is adjustably connected by a stud 209 pivotally connected to the casing and extending through the upper part of the frame and adjustably secured thereto by nuts 210 and 211 on such stud. The motor includes a pulley 215 which drives a belt 216 and this belt in turn drives a pulley 218 mounted on a shaft projecting into the transmission as presently will be described. For driving the cylinder 12 the transmission has a shaft 220 which carries a pulley 221 about which a belt 222 is trained. Such belt engages the large pulley 70 which drives the cylinder. It is to be observed that the transmission and motor are at opposite sides of the bar 204 but the transmission is heavier and through its greater weight holds the pulley 221 operatively.

engaged with the belt although it should be evident that if ever necessary, the transmission may shift upward slightly to relieve the strain in the event of unexpected load conditions.

Referring to Figure 5, the belt 216 is trained about a drive pulley 225 which is keyed to a main drive shaft 226. This drive shaft is journaled in a ball bearing 227 mounted in an arm 228 which in turn is secured by screws 229 to a pump housing cover plate 230. Such arm forms part of a larger cover 231 for the transmission casing and in this connection attention is directed to Figure 12 which shows that the arm 228 and the larger cover 231 are connected by a joining yoke 233. Inwardly of the pump housing plate 230, the shaft is fastened to a pump rotor 235 and the pump housing is completed by a casing 236 secured by screws 237 to the plate. The pump housing includes an inlet 238 located centrally of the pump and an outlet 239 and the use of the pump will be explained presently in greater detail in connection with other parts of the machine. The shaft 226 at its other end is journaled in a sleeve bearing 240 located in a hub portion 241 of the cover 231 and projects into the transmission housing indicated at 242 which is connected by bolts 243 (Fig. 6) to the cover.

Still referring to Figure 5, the shaft 226 within the housing has a clutch indicated generally at 245 and this clutch includes an end plate 246 which has driving engagement with the shaft by means of flats 247. This end plate abuts a shoulder 248 on the shaft so that the plate is held against axial movement towards the cover plate 231. A second end plate 249 is drivingly connected to a gear 250 turnably mounted on a sleeve 251 keyed to the shaft also by means of the flats 247, and the plate has an outer, axial flange 253. This flange at one or more points has an axial slot 254 which receives tongues 255 on three clutch plates 256, 257 and 258. Additional clutch plates 260 and 261, arranged in alternating relation to the plates 256, 257, and 258 are keyed as indicated at 262 to the sleeve. Between the end plate 249 and plate 258, a pressure ring 263 is provided for pressing the clutch plates together and the ring assembly against the end plate 246 when the gear 250 is moved to the left. It should be evident that when the gear is moved to the left, the plates are frictionally engaged and lock the sleeve to the plate 249 and gear 250 so that the latter will be rotated by the shaft. When this pressure on the gear is released, the clutch plates will separate sufficiently to allow the shaft to rotate relative to the gear. A spring washer 265 is provided between the inner end of the sleeve and the plate 246 for insuring separation of the plates when pressure on the gear 250 is released.

The other end of the sleeve receives the end of a second shaft 264 having flats 266 which drivingly connect the sleeve thereto and this second shaft has an integral pinion portion 267. Washer means 268 are provided between the latter and the sleeve and when the second shaft is shifted to the left, the gear and sleeve will be moved therewith so as to cause the clutch to engage. Beyond the pinion portion 267, the shaft 264 is journaled in a sleeve bearing 270 mounted in an arm 271 secured to the casing. Axial movement of the shaft 264 for clutch engagement is effected by means of a slide bushing 275 mounted in a portion 276 of the arm 271 and this bushing contains a spring 277 which presses against a ball 278 seated in a recess 280 in the end of the shaft. Movement of the bushing 275 is effected by a

cam actuated arm 283 pivoted, as indicated, at 284 on the arm portion 276 and such cam arm carries an adjustable screw 285 engaging the end of the bushing. At its other end, the cam arm

5 283 carries a cam engaging roller 286 for effecting periodical movement of the arm as will be explained hereinafter in connection with the general cam control of the machine. From the description so far, it should be evident that the gear 250 may be drivingly connected to the shaft 226 when the shaft 264 is shifted by the cam arm and it should also be evident that the pinion portion 267 on the shaft 264 is constantly driven.

Still referring to Figure 5, a lower counter shaft 290 is journaled in bearings 291 and 292 in the cover 231 and housing 242, respectively, and this shaft has a gear 294 keyed thereto as indicated at 295 which is in mesh with the gear 250. A large pinion 300 loosely mounted on the shaft 290 and meshing with the smaller pinion portion 267 on the shaft 264 has a one-way driving connection 301 with shaft 290 and this connection includes a nut 302 having an internal spiral thread 303 engaging a similarly threaded sleeve 304 keyed as indicated at 307 to the shaft. This sleeve is held in fixed axial position on the shaft by the gear 300 and the gear 294. The nut 302 has radially extending clutch teeth 305 on one side face which are adapted to engage recesses 306 on the side of the pinion 300 when the nut 302 travels axially. In order to cause the nut to travel axially, a spring retarder wire 310 is disposed in an annular groove 311 in the periphery of the nut 301 and one end of this retarder 310 has an eye 312 which is connected to a pin 313 on the pinion 300. In length, the retarder 310 is almost completely annular and it resiliently grips the bottom of the groove 311.

It should be evident that if the gear 300 begins 40 to rotate relative to the shaft 290, as for instance, when the machine is started and the clutch 245 is not engaged, the pinion 300 will begin to rotate and its rotation will tend to turn the nut 301 through action of the retarder wire 310 and rotation of the nut causes it to travel into engagement with the gear. When such engagement occurs and the nut may no longer travel axially, it must of necessity drive the sleeve 304 and consequently the shaft 290. If the shaft 290 is being 45 driven in this manner and the clutch 245 is engaged, the gears 250 and 294 will cause the shaft 290 to rotate more rapidly than that rotation resulting from the driving of pinion 300, and as a result, the faster rotation of sleeve 300 will 50 reverse the movement of nut 301 so that it will be disengaged from the pinion 300. During this faster rotation, the retarder 310 will idly slide on the nut. From this description it should be 55 clear that the shaft 290 may be rotated slowly by driving through the pinion 300 and driven more rapidly by driving through the gear 294 when the clutch 245 is thrown into engagement.

It might be stated at this time that the cylinder is adapted to be rotated a number of revolutions 60 in one direction and then through a number of revolutions in another direction and so on during washing and rinsing operations and that the speed of such rotation will not reach more than 48 to 52 R. P. M. On the other hand, for extracting moisture from the clothes, the cylinder 65 is to be rotated at a much higher speed, say 375 R. P. M., and this rotation will, of course, occur in one direction only. By throwing the clutch 245 into engagement, the high speed rotation will be effected and when this clutch is

thrown out of engagement the lower washing speed will be effected. It follows now that between the shaft 290 and the cylinder, mechanism must be employed to effect the reversing rotation as mentioned and then the one direction high speed.

Now referring to Figures 4, 5 and 8 jointly, it will be noted that a second counter shaft 320 is mounted parallel to the shaft 290 and is journaled in bearings 321 and 322 in the cover 231 and housing 242 respectively. The shaft 290 (Fig. 5) carries a pinion 323 adapted to be clutched thereto and this pinion meshes with a pinion 324 on shaft 320 and which is keyed thereto as indicated at 325. The shaft 290 is also provided with a second pinion 326 keyed thereto as indicated at 328 and which meshes with an idler gear 330 mounted on a stub shaft 331 carried by the housing 242. In turn, the idler gear meshes with a gear 332 on shaft 320 which is adapted to be clutched to such shaft. It should follow from this brief description that if gear 323 is clutched to shaft 290 while gear 332 on shaft 320 is unclutched, the shaft 320 will be driven in one direction, whereas if gear 332 is clutched to shaft 320 and gear 323 is unclutched from shaft 290, the shaft 320 will be driven in the other direction. As shown by Figure 8, the shaft 320 extends out of the casing and is drivingly connected to the pulley 221 previously mentioned and which drives the large pulley 10 connected to the cylinder. The means for clutching the one gear and unclutching the other now will be described.

With particular reference to Figure 8, the clutching means for connecting shaft 320 to gear 332 includes a sleeve 334 which is keyed to the shaft as indicated at 335 and also secured thereto against axial movement by set screws 336. At one end the sleeve has an opening 337 substantially fitting the shaft and this portion opposite the key 335 has an axial slot 340 receiving a shifting bar 341 which has at its inner end a tongue 342. At its other end the sleeve 334 has a larger opening 343 to receive a coil-type clutch spring 344 which is disposed over a sleeve 345 mounted on the shaft. One end of the spring has an axial projection 346 extending into a slot 347 in the gear 332 and it also is to be noted that a plurality of convolutions of the spring at this end thereof fit in a cylindrical opening or recess 348 in the gear. The other end of the spring indicated at 350 is disposed for engagement by the tongue 342 when the bar 341 is shifted axially for this purpose. Shifting of the bar 341 is effected by a clutch shifting sleeve 351 having an annular groove 352 and such sleeve is slidable on the sleeve 334. One end of the sleeve has an inturned flange 355 formed with a central opening receiving the shaft and at one point the flange has a radial slot 356 receiving the bar 341. Such bar likewise has a slot 357 engaging the flange at the outer end of the slot 356 and from this, it follows that the bar is not only shifted axially by the sleeve 351 but also rotates such sleeve.

When the sleeve 351 is shifted to the right from its position shown in Figure 8, the tongue 342 will be pressed against the end coil and as soon as it turns sufficiently, it will engage the end 350 of spring and begin to turn the latter. A small expansion of the spring quickly brings it into engagement with the wall of opening 343 and the surface of opening 348 in sleeve 334 and gear 332 respectively. This drivingly connects the sleeve and gear and since the sleeve is driven

by a shaft, the gear is accordingly driven by the shaft.

The same kind of clutching device is provided on shaft 290, as indicated at 360, and includes a shifting sleeve 361, a spring 362 and a sleeve 363 corresponding to like parts in Figure 8. When the sleeve 361 is shifted to the left, the gear 323 thus can be drivingly connected to shaft 290. However, the two clutch devices are oppositely arranged and if the clutch sleeves 351 and 361 are moved together as will presently be shown, one clutch engages while the other disengages and vice-versa. As a result, the shaft 320 is first driven in one direction and then in the other as the clutch sleeves are driven, and it follows that the washing machine will be similarly driven. Control of the mechanism therefore, only requires that the clutch sleeves 351 and 361 be shifted simultaneously and periodically and that at predetermined times the clutch 245 be engaged to effect high speed operation. It may be mentioned too that means are provided, as presently will be described, to insure that the high speed rotation will occur only at a time when the cylinder is rotating at the slower speed in the same direction that high speed rotation is to occur.

Now directing attention to Figures 4, 5 and 6, a cam shaft 375 is arranged above the two shafts 290 and 320 and this shaft has its ends journaled in cover plates 376 and 377, secured to the casing. As best shown by Figure 6, this shaft has a hub 379 turnably disposed on the shaft and such hub carries a ring gear 380 drivingly fastened to the hub. The gear meshes with a worm 381 shown by Figures 4 and 5 and the worm in turn is fixed to a shaft 382 journaled in the upper part of the fixed arm 271. A large gear 383 drives the shaft 382 as shown by Figure 5 and this gear meshes with the pinion portion 267 on shaft 264.

Referring to Figure 6, the hub 379 at one point adjacent its periphery carries a small pinion 385 which meshes with a large gear 386 keyed, as indicated at 387, to the cam shaft. The pinion 385 also meshes with a ring gear 388 fixed to the casting plate 377 and this ring gear has one tooth less than the gear 386. It should follow that when the small pinion 385 rolls around the periphery of the ring gear 388 and the ring gear 386, its rotation around its own axis will be governed by the ring gear and since the gear 386 has one more tooth, the latter gear will advance one tooth for each revolution of the hub 379. The cam shaft 375 therefore turns very slowly and in actual use it will turn only one revolution in, for example, 45 minutes.

The hub 379 also carries a cam 390 which may be termed the reversing cam and this cam serves to shift the two clutch sleeves 351 and 361 periodically. Additionally, the cam shaft carries what may be termed a synchronizing cam 391 which is provided for the purpose of insuring that the high speed rotation will be initiated only when the cylinder is turning slowly in the same direction as that at which high speed rotation will occur.

For controlling high speed rotation through control of clutch 245, a high speed cam 392 is provided on the cam shaft and adjacent this cam a switch controlling cam 393 is provided for controlling the motor circuit. Another cam 394 controls the drainage of water from the tub. The cam shaft projects from the casing plate 376 and the projecting end is provided with a cam 397 for controlling the inlet water. This cam can be shifted axially to vary the temperature of the inlet water and this action will presently be de-

scribed in more detail. All of the cams 392, 393, 394 and 397 are keyed to the shaft but the cam 391 is connected thereto by a play-permitting connection and this will be described presently in connection with Figure 12.

Now directing attention to Figure 13 in connection with the reversing cam, it will be observed that the cam has a dwell 400 and a land 401 and the ends of the two portions joined by inclines 402 and 403. The land and dwell portions are of equal length so that the cylinder will turn approximately the same number of revolutions in each direction during washing and rinsing. This cam is engaged by a roller 405 carried by a channel arm 406 which is turnable on a stationary pin 407 and the arm receives within its channel, a second arm 408 which at one end engages an adjustable set screw 409 extending through the base of the channel. At the opposite side of the pivot 407, the arm 408 has a cavity 410 receiving a spring 411 which presses against the base of the channel so as to hold the screw 409 against the arm 408 while allowing relative movement through compression of the spring. At its outer end, the arm 408 has a pin 412 and, as best shown by Figure 14, this pin carries rollers 413 and 414 which project respectively into the annular grooves in clutch shifting sleeves 351 and 361. It should now be evident that if arm 408 is shifted, it will simultaneously shift the two clutches on shafts 290 and 320 so as to engage one and disengage the other. It follows that as cam shaft 390 rotates, the cylinder may be rotated in alternate directions.

Referring to Figure 5, the high speed cam 392 has low portions 415, 416 and 417 and when the roller 286 is in contact with the low portions, the high speed clutch 245 is disengaged. The cam also has high portions 420, 421 and 422 and when roller 286 is in contact with these high portions, the high speed clutch is engaged. Cam portions 420 and 421 are short and represent in the cycle of operations a short high speed spin at the end of the washing phase and a second short high speed spin at the end of the first rinse. The larger cam portion 422 represents the high speed drying stage.

The cam 391, seen best in Figure 12, is provided to insure that the roller 405 engaging cam 390, shown in Figure 13, will not drop into engagement with the low part 400 of the cam when the high speed rotation is to occur. This result is obtained in the following manner. The channel arm 406 has a roller 425 engaging the cam 391 and this cam has a long high portion 426 acting in the high speed drying stage, and smaller high portions 427 and 428 acting in the minor spins previously mentioned. Between such high portions the cam 391 has low portions 429, 430 and 431. The cam 391 is driven by an arm 434 fastened to the cam shaft 375 and this arm has a pin 431 projecting into a larger opening 432 in the cam. The arm is connected to the cam by a spring 433 and normally when the arm 434 turns with the cam shaft it drives the cam through the spring although a positive drive would be effective if the arm 434 moved far enough to engage the side of opening 432. Normally the spring will do the driving and the enlarged opening permits some movement of the arm relative to the cam.

It will be noted that the arm 408 also has a through opening 440 and that a spring 441 disposed in this opening presses at one end against a stationary part 442 while its other end presses

against the base of the channel 406. Viewing Figures 12 and 13 together, it is evident that the spring 441 urges the channel arm against both cams while the spring 411 holds arm 408 in a certain position with respect to arm 406.

The cam 391 in Figure 12 is in a position substantially at the end of the machine operation and in this position the roller 405 is so related to cam 390 that it is at least raised to the level of the high part 401 of the latter. This means that the cylinder is so controlled by the reversing clutches that it must travel in one direction, namely the direction governed by the arm 408 when it is in the position shown in Figure 13. Now if the cam 391 turns slowly in the direction indicated by the arrow in Figure 12, it reaches a position where it is ready to drop off of the high part of the cam to the long low part 431 thereof and it will do so as soon as the low part 400 of cam 390 reaches the roller 405. This will occur rather quickly because the cam 390 is traveling much more rapidly than cam 391. It might be noted at this time that a neutral step 445 is provided at the dropping off side at each of the high parts 426, 427 and 428 on cam 391 and under certain circumstances this is desirable to prevent the roller 405 from dropping suddenly to the low part 400 of cam 401 at the end of any high speed operation. In other words, at the end of any high speed operation, a neutral condition is obtained before the cylinder can reverse.

As the cam 391 continues to turn in the direction indicated by the arrow in Figure 12, the roller 425 is disposed over the long low part 431 of the cam and when so located, the arms 406 and 408 will be oscillated about the pivot 407 by cam 390 and during the time roller 425 is relatively moving from the high portion 426 to the high portion 427 of cam 391 the cylinder is being reversely rotated. When the high part 427 of cam 391 finally reaches the roller 425, it engages it squarely if the roller 405 is down on the low side 400 of the cam 401 and in this event, the arm 434 advances relative to cam 391, but just as soon as the roller 405 is moved outwardly by the high part 401 of cam 390, cam portion 427 is thrown under roller 425 by spring 433 and then the arm 406 is held in its outer position. As long as roller 425 is over cam portion 427, cam 390 can continue to rotate without any effect on the reversing mechanism and only one of the reversing clutches will be engaged. The arrangement is such that always when roller 405 is in the position shown by Figure 13, the cylinder is turning in the high speed direction and consequently high speed rotation always picks up the cylinder when it is traveling in the same direction as the high speed rotation. This same procedure occurs for each of the high parts of cam 391.

The switch control cam 393 shown by Figure 11 has drop off 450 at one point and such cam cooperates with a plunger 451 adapted to actuate a switch 452 in the circuit of the motor. The switch is in its closed position in Figure 11 and in order to start the machine, a relay is employed as will readily be understood, and then as soon as the switch 452 is closed by movement of the cam, the relay is cut out and the motor is controlled solely by the switch. It might be mentioned at this time that the door 150, as seen in Figure 2, is adapted to control the motor circuit also and, as shown, a switch 455 is provided which has a plunger 456 in the path of one of the hinges 151. If the door is opened for any reason,

the motor circuit is interrupted but as soon as the door is closed, the switch 455 is closed.

The foregoing description relates to operation of the mechanism and provides a control for reversing the cylinder at predetermined times and also rotating it at high speed at predetermined times. During any cycle of operations it is necessary to have water enter the tub at certain periods and to have the water drained. The controls for water entering the tub and draining therefrom are also operated by the cam shaft. Referring to Figures 6, 15 and 16, the cam 397 has one recess 460 which is located between the ends of the cam and two additional recesses 461 and 462 which open at one end of the cam only and terminate intermediate the ends of cam 460. This cam is adapted to control the inlet water and referring to Figure 6 in particular, the inlet valve is indicated at 464 and substantially corresponds to the valve shown in the applications for patent previously identified. This valve includes a hot water inlet 466 and a cold water inlet 467 and water flows from this valve to the tub by means of an outlet 465. Water is adapted to be mixed in the valve to permit two temperatures and the lower temperature, for instance 100°, is controlled by a valve 468 while the higher temperature, for instance 140°, is controlled by a valve 469. Such valves are operated by sprung fingers 470 and 471 riding on cam 397.

As shown by Figures 15 and 16, the finger 470 is in a position where it will drop into all three recesses 460, 461 and 462 so that water at the lower temperature will be supplied with the cam in the position shown. However, if the cam 397 is shifted to the right, as seen in Figure 16, the recess 460 will be shifted to a position where it will not be engaged by finger 470 but only by finger 471 although finger 470 will still be in a position where it will drop into recesses 461 and 462. This means that with the cam 397 in one position, water at the lower temperature will be supplied at all three stages, but if the cam 397 is shifted, water at the higher temperature will initially be supplied for washing while water at the lower temperature will be supplied for the rinsing stages.

The water line 465, as shown by Figure 2, leads from a solenoid controlled valve 475 and the solenoid for this valve is in a circuit completed only when the motor is energized so that the valve is open only while the machine is in operation. Of course, the water supply is cut off by the two fingers 470 and 471 when they are in contact with the high parts of cam 397, so that water will be supplied to the tub only when one of the fingers drops into one of the cam recesses.

Shifting of cam 397 is effected, as best shown by Figure 4, by a push and pull wire 480 connected to an arm 481 pivoted as indicated at 482 on an ear integral with the cover element 376. This arm has a portion 483 which projects into a groove 484 in the cam. The wire 480 leads to the control panel 131 on the front of the cabinet and is adapted to be pushed and pulled by turning a finger control 485 thereon. Any suitable connection may be provided for this purpose as may be readily understood. A second finger control 486 on the control panel is employed to operate the relay previously mentioned which starts the machine.

As shown by Figures 1 and 2, a conduit 501 leads from the water line 465 and a substantial part of this conduit may be rubber to permit flexing as required. The rubber part of the conduit joins a metal conduit 501 shown by Figure 1

which leads upwardly at the outside of frame 19 and at its upper end it has reverse bend 502 held in place by a bracket 503 welded to the conduit and connected to the frame. The open end of the reverse bend 502 is indicated at 504 and is directly above an entry or funnel 505 secured to the frame and located over an opening 506 therein. It is to be observed that the end 504 is substantially above the funnel so as to eliminate any possibility of water in the tub entering the inlet conduit in the event any vacuum condition ever occurred in the latter. At the inner side of the frame a baffle 507 is provided to prevent splashing water from being thrown out through the funnel or entry during operation of the machine.

A second, smaller conduit 509 also leads to the funnel 505 and this second conduit is connected to the pump as shown by Figure 5. As will be seen presently, the inlet side of the pump is connected to the tub and with the pump constantly driven, water from the tub is constantly pumped back through the conduit 509 and again into the tub through the funnel. A small stream of water thus constantly flows into the funnel and this water acts to break or beat down soap suds tending to discharge through the funnel and in this way the tendency of suds to leak from the machine in the event of oversoaping, is avoided.

The bottom of the tub, as best shown by Figure 2 has a drain opening 515 and over this opening a discharge chamber 516 is provided which is connected to the tub by bolts 517. This chamber has a cylindrical portion 519 and within the cylindrical portion a cylindrical screen 520 is provided for the purpose of collecting lint and other foreign matter. The cylindrical part 519 of the chamber 516 has a discharge port 522 and this discharge port is connected by a flexible conduit 523 to the pump inlet 238. The discharge side of the pump 239 is connected to a drain valve indicated generally at 524 which in turn has a drain connection 525.

The open lower end of the discharge chamber 519, as shown in Figure 2, is closed by a cover plate 530 and such cover plate at its center is pivoted as indicated at 531 to an arm or hand lever 532 having a finger gripping portion 533. A second arm portion 534 fixed to the arm 532 has a notch 535 which receives the base portion of a U-shaped wire or bail 536 having side legs extending along the chamber 519 and inturned ends 538 fulcrumed in openings provided in bosses on the side walls of the chamber at diametrically opposed points. If, as seen in Figure 2, the finger grip 533 is pulled outwardly, the base portion of the U-shaped wire will be thrown upwardly above the pivot 531 and then it is easily released from the notch 535 and thereafter the wire may be swung over the upper part of the cover and the cover can be withdrawn through the opening normally covered by the door 119. After the cover is withdrawn, the screen 520 can be withdrawn and cleaned. Assembly can be effected in the reverse order of that mentioned.

The drain cam 394, as best shown in Figure 10, has three high portions 540, 541 and 542 adapted to raise a plunger 543 which lifts an arm 544 pivoted as indicated at 545 on an upper cover 231 of the casing. The arm 544 is connected to a link 547 which in turn is connected to a valve arm 549 pivoted as indicated at 550 on the casing of valve 524 at the discharge side of the pump and this valve arm inside the casing carries a valve 552 adapted to open and close a discharge port 553.

leading to the drain connection 525. It should be understood that even though this valve is closed, the pump can still operate since in that case the rotor will merely have an idling movement in the pump.

The general operation of the machine is as follows: In order to insert the clothes, the operator turns the handle 190 so as to actuate latch 161 and release the door cover 150 and then the door is manually moved to its fully open position. This movement of the door opens the switch 455 in the motor circuit and therefore prevents any possible operation of the machine while the door is open. The cylinder 12 is now turned until its door 73 is uppermost and then the door is opened so that the clothes may be placed in the cylinder. In this connection it might be noted that the cylinder may be easily turned manually in view of the fact that the high speed clutch 245 (Figure 5) is disengaged and in view of the fact that the one-way drive 301 between shaft 290 and gear 300 permits the shaft to be turned easily in that direction in which the one-way drive is idle. After the clothes are inserted, sufficient soap is added and then the cylinder door 73 is closed. Following this, the cabinet door 150 is closed and when the latter door is closed the switch 455 is also closed so that the machine is now ready for operation.

Before starting the machine, the operator should determine the temperature of the wash water to be used and if water at the higher temperature is to be used, the control 485 on the cabinet is turned so as to shift the cam 397 to the right, as seen in Figure 16. Following this selection of temperature of the wash water, the operator turns the other control 486 on the cabinet and this closes a relay circuit which starts the motor and machine operating. With particular reference to Figure 10, the cam 394 will at once move so as to allow the drain valve to close and at approximately the same time, the finger 471 as seen in Figures 15 and 16, will drop into the cam recess 460 and this will open the water inlet valve and allow water to enter the tub. Water will continue to flow into the tub as long as the finger is in the cam recess 460 and then the inlet valve will automatically close as the finger rides out of the recess.

Directing attention now to Figure 11, as soon as the machine starts operating with the relay circuit closed, the switch cam 393 begins also to turn and as the cam surface 450 passes the switch pin 451, the switch 452 closes and then this switch takes over the control of the motor circuit and at the same time the relay circuit automatically is broken.

As will be evident from Figures 12 and 13, the cylinder will start turning in one direction at a slow rate of speed as soon as the machine starts operating because the roller 405 is held in its outermost position and this causes the clutch 360, shown by Figure 5, to be engaged. Shortly after initial rotation of the cylinder, the roller 425, as seen in Figure 12, will drop to the lower surface 431 on the cam 391 and then reversing rotation of the cylinder will occur since the roller 405, in Figure 13, is now free to move in and out over cam 390. When the roller is in contact with the low surface 400 on the cam 390, the clutch on shaft 320 is engaged (Fig. 8) and the cylinder rotates in one direction and then when it is raised to come in contact with the surface 401, the clutch on shaft 290 (Figure 5) is engaged and rotation occurs in the other direction.

Washing of the clothes now occurs for a substantial period of time as, for instance, 15 minutes, and during this time the cylinder rotates first in one direction and then in the other. At the end of the washing phase of the cycle, the drain cam 394, as seen in Figure 10, has turned to such a point that the high part 542 on the cam causes the drain to open so as to allow the water to drain from the tub. At about the same time, as will be seen in Figure 12, the high part 427 on the synchronizing cam will have reached the roller 425 and then it will move under this roller when the roller 405, in Figure 13, is on the high part 401 of cam 390. The cylinder can now turn only in one direction, which is the same direction as that at which subsequent high speed rotation occurs, since the roller 405 in Figure 13 is maintained in its outermost position regardless of cam surface 400. After this has occurred, the high point 420 on the high speed cam 391, as seen in Figure 5, moves roller 286 and causes the high speed clutch 245 to engage and then the shaft 290 is driven in overrunning relation to the one way drive 301 and the cylinder rotates at high speed so as to obtain an intermediate high spin after the washing stage. This is desirable so as to cause the soapy water to be thrown from the clothes and to drain out of the tube. This high speed action occurs only for a short time and then the high speed clutch is disengaged and the cylinder slows down and again is driven by the drive 301 and in the same direction but at the slow speed. An instant later the roller 425 in Fig. 12 drops off of the high part 427 of the synchronizing cam 391 and then the roller 405 is free to move in and out on cam 390 and reversing rotation again takes place.

Approximately at the time the first high speed spin ends, the high part 542 on the drain cam 394 in Figure 10 passes the pin 543 and then the drain valve closes. At about this time also the finger 470 drops into the recess 461 on the inlet valve cam 397 and then water at the lower temperature enters the tub until the finger rides out of the recess. A rinsing stage now occurs with clean water in the tub and with the cylinder rotating in a reversing manner. This rinsing occurs for a short period of time and then the drain valve is opened by the high part 541 on the drain cam 394 and a second high speed spin occurs when the high part 421 on the cam 392 in Figure 5 causes the clutch 245 to engage. Following this second high speed spin, the drain valve closes when the high part 541 of cam 394 (Figure 10) passes pin 543 and then fresh water enters the tub as the finger 470 drops into and rides in the cam recess 462. A second rinse now occurs with the cylinder again rotating in a reversing manner.

After the second rinse, the long high part 540 of the drain valve in Figure 10 reaches the pin 543 and the drain valve opens. At about the same time the high part 426 of the synchronizing cam in Figure 12 reaches the roller 425 and then as the roller 405 (Figure 13) reaches the high part 401 on cam 390, the cylinder is allowed to rotate only in the one direction again. Shortly after the synchronizing cam functions to insure rotation of the cylinder only in this one or high speed direction, the high part 422 of the high speed cam 392 in Figure 5 engages the roller 286 and causes the high speed clutch to engage. A high speed drying stage now follows for a substantial period of time during which the clothes are brought to a semi-dry condition through cen-

trifugal drying action. Just before the cam 393 in Figure 17 allows the switch 452 to open, the roller 286 drops onto the lower surface 415 of the high speed cam in Figure 5 so as to cause the high speed clutch to be disengaged. Shortly after this occurs, the switch 452 is allowed to open as the pin 451 drops onto the surface 450 of cam 393 and the machine stops. This brings all of the cams and other parts of the machine back to the positions and relations shown in the drawings with the drain valve still open and the inlet valve closed. It is only necessary now to turn the handle 190 to open the door 150 and then to move the cylinder manually until its door is uppermost. The clothes can now be removed and hung up to dry.

Although only one form of the invention has been illustrated and described in detail, it will be apparent to those skilled in the art that various modifications may be made without departing from the scope of the claims.

What is claimed is:

1. A washing machine transmission comprising a driven shaft for moving a cylinder in the machine, a second shaft parallel to the driven shaft, a loose gear on each shaft, a gear keyed to each shaft, one of the loose gears meshing with one of the keyed gears, an idler gear between the other two gears and meshing therewith, clutch means for drivingly connecting each of the loose gears to its shaft, automatic means for alternately engaging the clutches, means for driving the second shaft at a high speed for drying the clothes in the cylinder, speed change means for driving the second shaft at lower speed for washing the clothes, automatic means for controlling the speed change means, and synchronizing means for preventing said first mentioned automatic means from alternately engaging the clutches and for maintaining one of the clutches in engagement when the high speed rotation occurs.

2. In a washing machine having a tub, and a turnable cylinder in the tub which is to be rotated slowly in a reversing manner for washing and rinsing the clothes and then rotated at relatively high speed in one direction for drying the clothes, a motor driven drive shaft, a second shaft, gear means on the drive shaft and second shaft including a clutch so that the second shaft can be operatively disconnected and connected to the drive shaft, gear means including a one way drive between the drive shaft and second shaft for driving the second shaft relatively slowly as compared to the speed of the second shaft when driven through said clutch, means for periodically causing the clutch to be engaged so as to effect driving of the second shaft thereby, a third shaft drivingly connected to the cylinder, means including a pair of clutch means between the second and third shafts to effect reversing rotation of the third shaft, and means for rendering one of said pair of clutch means inoperable to prevent reversing rotation of said third shaft and for maintaining the other of said pair of clutch means operable to effect rotation of said third shaft in one direction when the second shaft is rotated at its higher speed.

3. A transmission for a reversely operating cylinder of an automatic washing machine, comprising a motor driven drive shaft, a second shaft having alternately operable high and low speed

connections with said drive shaft, a third shaft adapted to be connected to the cylinder and having alternately operable connections with said second shaft for driving said third shaft in opposite directions, and control means driven by said drive shaft for rendering one of said connections between the second and third shafts inoperable and for maintaining the other operable when the high speed connection between the drive shaft and the second shaft is operable.

4. A transmission for a reversely operating cylinder of an automatic washing machine, comprising a motor driven drive shaft, a second shaft having alternately operable high and low speed connections with said drive shaft, a third shaft adapted to be connected to the cylinder and having alternately operable connections with said second shaft for driving said third shaft in opposite directions, and control means comprising gearing connected to said drive shaft, cam means driven by said gearing for alternately rendering said connections between said second and third shafts operable to effect reversing operation of said cylinder, and other cam means driven by said gearing for rendering said first mentioned cam means inoperable and for maintaining only one of the connections between the second and third shafts operable when the high speed connection between the drive shaft and the second shaft is operable.

5. A transmission for a reversely operating cylinder of an automatic washing machine, comprising a motor driven drive shaft, a second shaft having alternately operable high and low speed connections with said drive shaft, a third shaft adapted to be connected to the cylinder and having alternately operable connections with said second shaft for driving said third shaft in opposite directions, and control means comprising a first cam means for alternately rendering said connections between the second and third shafts operable to effect reversing operation of the cylinder, a second cam means operable at predetermined periods for rendering the first cam means inoperable and for maintaining only one of the connections between the second and third shafts operable, and a third cam means for rendering the high speed connection between the drive shaft and the second shaft operable during said predetermined periods.
